(57) **CLAIM**

The ornamental design for a cap for a container as shown and described.

DESCRIPTION

1. Cap for a container

1.1 is a left side elevation view of a cap for a container showing our new design;

1.2 is a front side elevation view thereof;

1.3 is a bottom plan view thereof;

1.4 is a perspective view thereof;

1.5 is a rear side elevation view thereof;

1.6 is a right side elevation view thereof;

1.7 is a top plan view thereof; and

1.8 is a cross-sectional view thereof taken at 1.8-1.8 in Fig. 1.1.

The design shows a cap for a container, namely ink or solvent for an inkjet printer. In the reproductions, the dot-dash broken lines immediately adjacent to the claim depict the bounds of the claimed design and form no part of the claimed design, while all other dot-dash broken lines and all dash-dash broken lines are directed to environment and form no part of the claimed design.
